UNITED STATES PATENT OFFICE.

LOUIS LA BORIE, OF ROCHESTER, N. Y.

PICTURE-MAKING APPARATUS.

1,425,597.

Specification of Letters Patent. Patented Aug. 15, 1922.

Application filed February 3, 1921. Serial No. 442,264.

To all whom it may concern:

Be it known that I, LOUIS LA BORIE, of Rochester, in the county of Monroe and State of New York, have invented certain 5 Improvements in Picture-Making Apparatus; and I do hereby declare the following to be a full, clear, and exact description of the same, reference being had to the accompanying drawings, forming a part of this 10 specification, and to the reference numerals marked thereon.

My present invention relates to games and toys and more particularly to amusement devices for making or reproducing pictures 15 and it has for its object to provide an apparatus in the nature of a drawing book of improved form and designed to enable very young children to make fairly accurate copies of figures, pictures or outlines as 20 formed upon guide sheets constituting part of the apparatus. The improvements relate in part toward providing a plurality of such guide sheets in convenient form and furnishing a suitable and convenient tablet 25 or writing surface for selective use with any one of the guide sheets. To these and other ends the invention resides in certain improvements and combinations of parts all as will be hereinafter more fully described, 30 the novel features being pointed out in the claims at the end of the specification.

In the drawings:

Figure 1 is a plan view of a drawing book constructed in accordance with and illustrating 35 one embodiment of my invention, the same being shown extended and with the tablet or writing surface in inoperative position;

Figure 2 is an enlarged fragmentary view 40 of the book with the tablet in operative position, and

Figure 3 is a longitudinal section taken on the line 3—3 of Figure 2.

Similar reference numerals throughout 45 the several views indicate the same parts.

In the present instance, I have illustrated a book embodying a plurality of stencil sheets showing the outlines of animals or similar objects that are to be traced by the 50 child and then colored or otherwise elaborated or used. The book comprises back pieces 1 and 2 to which are respectively connected by flexible leather or other hinges 3 a back cover 4 and a front cover 5. The 55 back pieces are held together by a known type of two part threaded posts 7 and the

stencil or guide sheets 8 are perforated at one edge to receive these posts and clamped by them between the back pieces 1, as shown in Figure 3, to constitute the leaves of the 60 book. They may be secured or otherwise fitted along lines closely adjacent to the back pieces to turn or fold readily in the manner of a book leaf. Each guide sheet, in the present instance, is cut out to produce 65 the stencil outline of an object as a lion, indicated at 9, and a fish as indicated at 10 on two adjacent sheets.

The back pieces 1, as described, are connected along one edge of each cover, and 70 hinged to another edge of one of the covers, preferably the back cover 4, is a tablet 11. In the present instance, this tablet is connected at the opposite edge of the said cover by a flexible leather hinge 12 so that the 75 leaves or stenciled sheets 8 and the tablet swing toward and from each other in the same vertical plane. The tablet may be made of any stiff, thin substance presenting a smooth writing surface and I prefer to 80 employ for the purpose a good grade of fiber board or cardboard. It may be fitted at its corners with triangular retaining pockets 13 one purpose of which is to hold a plurality of drawing sheets 14 slipped beneath them and detachable from the tablet 85 when used. These are the receiving sheets upon which the pictures are made. The hinge 12 of the tablet gives sufficient flexibility and range to the swinging movements of the latter to permit it to be inserted selectively 90 between any two or beneath any one of the guide sheets 8.

In using the device, the book is opened to the guide sheet or stencil 8 that is selected for reproduction as, for instance, the one bearing the outline of the lion 9 in the figures. This sheet is raised and the tablet 11 folded down beneath it as shown in Figure 2 to rest upon the pile of leaves or 100 stencils beneath. The guide sheet is then folded down from the other direction to a superposed position upon the tablet as in Figure 3 and preferably the free corners thereof are caught beneath the corner retaining pockets 13 near the hinge of the tablet to further insure that the latter and the guide sheet will be maintained in proper relationship. The child now traces with a pencil or other instrument the outline 9 upon 105 the uppermost receiving sheet 14 and then folds the stencil sheet back again, whereat 110

the picture produced may be worked on and elaborated as by coloring, still using the tablet 11 as a drawing board. When finished, the picture is easily detached and the 5 next one below is ready to receive an outline from the same or another selective guide sheet in the same manner.

A tablet so mounted in a book of this kind not only makes it easy for the child to keep 10 the paper and the guide sheet in fixed relationship while the tracing is being done but it provides a convenient and good writing surface that cannot be detached, lost or misplaced and which is particularly necessary when stencils are used as the underlying 15 stencil is impossible for use as a writing surface.

I may fit one of the covers as the back cover 4 with a pocket 15 for the reception of 20 drawing sheets, crayons or other paraphernalia which will tend to make the whole outfit self-contained.

In using the word "tablet" herein, unless otherwise specified, I am using it in the 25 broad sense of a writing surface whether or not it contained a plurality of superposed blank sheets.

I claim as my invention:

1. In a picture making apparatus, the 30 combination with a support, of a movable guide sheet and a movable tablet adapted to support a picture receiving sheet beneath the guide sheet, the latter and the tablet being maintained in proper relationship by 35 the support.

2. In a picture making apparatus, the combination with a support, of a guide sheet hinged thereto and a tablet adapted to support a picture receiving sheet beneath 40 the guide sheet, the tablet being hinged to the support on an axis removed from that of the guide sheet.

3. In a picture making apparatus, the combination with a support, of a guide sheet 45 hinged thereto at one side of the support, and a tablet adapted to support a picture receiving sheet beneath the guide sheet, the tablet being hinged to the support at the opposite side so that two hinged elements 50 swing toward and from each other.

4. In a picture making apparatus, the

combination with a support, of a guide sheet hinged thereto and a tablet adapted to support a picture receiving sheet beneath the guide sheet, the tablet being hinged to the support on an axis removed from that of the guide sheet, and being provided with devices for temporarily catching and holding the free end of the guide sheet. 55

5. In a picture making apparatus, the combination with a support, of a guide sheet hinged thereto and a tablet adapted to support a picture receiving sheet beneath the guide sheet, the tablet being hinged to the support on an axis removed from that 60 of the guide sheet, and being provided with devices for retaining thereon a plurality of picture sheets, said devices also operating to temporarily catch and hold the free end of the guide sheet. 65

6. In a picture making apparatus, the combination with a book embodying a plurality of guide sheets bound together and provided with a cover, of a tablet adapted to support a picture receiving sheet beneath 70 any one of the guide sheets, selectively, said tablet being hinged to the cover along an edge thereof other than that to which the guide sheets are attached. 75

7. In a picture making apparatus, the combination with a book embodying a plurality of guide sheets bound together and provided with a cover, of a tablet adapted to support a picture receiving sheet beneath any one of the guide sheets, selectively, said 80 tablet being hinged to the cover by a flexible hinge attached to the latter at the opposite edge from that of the guide sheets. 85

8. In a picture making apparatus, the combination with a book embodying a cover 90 and a plurality of stencil sheets bound together along one edge of the cover, of a tablet having devices thereon adapted to detachably support a plurality of picture receiving sheets beneath any one of the stencil sheets, 95 selectively, said tablet being hinged to the opposite edge of the cover and the sheet holding device thereon being also adapted to temporarily retain the free end of a stencil sheet.

LOUIS LA BORIE.
